WINDOW ARRANGEMENT FOR FUME HOODS

John M. Liptay, Scarsdale, N. Y.

Application February 3, 1949, Serial No. 74,270

13 Claims. (Cl. 20—40)

1

This invention is an improved and serviceable fume hood having as one object the provision of a multiple closure system comprising a plurality of selectively controlled closure units including window frame carrying runners telescopically associated with projectible and retractable tracks slidably guided by vertically disposed guides above the common work surface of the fume hood, the closure units being adapted to provide prompt access to selective portions of the fume hood however unobstructed by mullions. Another specific object of the invention is realized in utilizing slidably guided telescoping members adapted to be conveniently collapsed in the matter of opening each unit and adapted to be quickly extended for closing its respective portion of the fume hood. Another important object resides in the provision of latching means on the runners for interlocking with the tracks on closing of the frames to project these tracks below the guide means. Another object is to provide a fume hood of the character alluded to wherein the entire work surface of the hood may be conveniently rendered accessible and without obstruction upon raising of all the window carrying frames. Other important functional and structural features of the invention will appear from the following detailed specification considered in the light of the accompanying drawings wherein:

Fig. 1 is a front elevational and fragmentary view of the fume hood according to my invention illustrating the multiple closure system partly opened and closed.

Fig. 2 is a fragmentary perspective view of Fig. 1.

Fig. 3 is a transverse vertical sectional view on the line 3—3 of Fig. 2.

Fig. 4 is a transverse horizontal sectional and broken view on the line 4—4 of Fig. 2.

Fig. 5 is a sectional view on the line 5—5 of Fig. 2.

Fig. 6 is an enlarged and fragmentary sectional view on the line 6—6 of Fig. 5.

Fig. 7 is a sectional view on the line 7—7 of Fig. 2.

Fig. 8 is a sectional view on the line 3—3 of Fig. 2.

Fig. 9 is a perspective view of one of the lower runners or rails illustrating its spring controlled normally retracted latch adapted to return the intermediate runners on closing of the window frames.

Fig. 10 is an enlarged fragmentary view of Fig. 3, and

2

Fig. 11 is a fragmentary perspective view of two of the units shown fully raised or open.

Representative of the embodiment disclosed, the fume hood generally designated MU is appropriately associated with support S characterized by the work surface WS which may form a part of cabinet C or may constitute the top surface of a floor on which the cabinet rests.

Effectively fixed to a wall WL of cabinet C in any suitable manner are outside angle irons as 10 and the spaced intermediate angle irons or brackets 11. These angle irons have secured thereto by bolts B and nuts N companion parts of spaced inner guide channels or tracks G and G' each of which is preferably C shaped as shown.

Slidably guided by or trained over guides G and G' and retained thereon are the reverse C shaped runners or intermediate tracks R and R' in turn slidably straddled and guarding the channel shaped runners RN and RN' fixedly secured to the sides 13 of the window sashes or frames F to each of which is fixedly attached lip or projection P welded at 14 (Fig. 8) to the channel shaped sill or block LB adapted to rest on work surface WS (Fig. 2).

More specifically each runner RN comprises an offset arm 15 (Fig. 4) merged with web 16 having the inwardly bent arm 17 fastened to a back retaining panel 18 and to an associated window frame F by appropriate screws as 19. If desired panel 18 may be welded to arm 17, the arrangement being such that arm 15 and companion panel 18 slidably straddle and are guided by an associated intermediate track R.

Runners RN' are characterized by a flange or arm 20, a web 21 and an inwardly turned arm 22 secured to the window frame F and to the back retaining panel or strip 23 by screws as 24 and strip 23 may be also welded to arm 22. Thus arm 20 and strip 23 of each runner RN' slidably straddle and are guided on an intervening track R'.

Of importance is the additional function of the offset arms 15 of the lower rails or runners RN which slidably overlap arms or components 20 of adjacent intermediately disposed runners RN', thereby facilitating linear and relative slidable displacement of juxtaposed runners RN and RN' and it should also be observed that suitable collars 12 are mounted on bolts B to adequately space the fixed guides G and G' from their companion angle irons 10 and 11 adequately anchored to the supporting wall WL desirably spaced and suspended appreciably above the work surface WS.

For sealing the rear face of the sill or block LB of a window frame F, a panel 45 is suitably welded thereto and to the frame F and fastened to the latter at the upper part thereof is an upper angle iron UC (Fig. 7) to which the channel shaped member or hollow upper block UB is appropriately welded and this block has its offset tail portion T effectively held to the frame F and to the angle iron UC in any suitable manner. Thus frame F, the upper and lower blocks UB and LB, and the runners RN and RN' move in unison when a thrust is applied to lip P in the process of raising or lowering of a selected window frame each of which is provided with a transparent window pane WP sealed by an adequately retained gasket K.

In Fig. 2, the window frames F are shown closed and therefore the lower blocks LB are resting on the work surface WS of the flooring, support or foundation S. As each frame is raised the laterally extending tongues or lugs as 50 and 51 projecting from the lower runners or channeled rails RN and RN' meet the lower ends LE and LE' of the slidably guided intervening tracks or channel shaped members R and R', thereby raising the latter relative to the upper tracks or guides G and G'. Such action however is facilitated by the spring counterweights or balancers CB mounted on a platform 52 intervening and desirably fixed to companion angle irons 10 and 11 and to pairs of companion intermediate angle irons 11. The spring tapes 53 of the balancers CB pass through relief and guide slots 54 (Fig. 2) and the lower ends are provided with swiveled loops 55 hooked to hasps 56, fastened to the upper block UB. Upward displacement of the frames F is limited by overhanging lugs as 57 extending from the fixed guides G fixedly suspended above the work surface.

On closing of a sash frame F, downward displacement of the tracks R and R' is limited by the laterally extending lugs 35 and 35' as the top parts thereof strike stop brackets as 36 and 36' fastened to the columns or guides G and G'.

In Fig. 1, four closure units W, X, Y and Z are shown associated with the common support or foundation S of a multiple fume hood MU, and each of the units is structurally identical and of course is suspended from a pair of companion angle irons 10 and 11 or from a pair of intermediate angle irons 11 appreciably above the work surface WS. Each unit may be controlled independently of the other and selectively operated. For example, in Fig. 1, frames F of units W and X are fully closed while those of units Y and Z are fully raised although all frames or any combination thereof may be fully or partly raised or closed. Thus by the present arrangement the work surface may be extended as desired without interference by intermediate posts or mullions.

Where the frames F are fully closed and resting on the work surface WS, the beveled bolts or latches as 60 and 60' (Figs. 2, 3 and 10) of each frame are movably disposed in openings 62 at the top part of the lower rails or runners RN and RN' and in openings as 61 at the top of the intermediate channel shaped tracks R and R'. These latches are fixed to a flange 63 larger than an associated opening 62 and each flange 63 is fixed to an offset leaf spring 64 (Fig. 10) secured at its lower end to the runners RN and RN'. Springs 64 normally urge latches or locking means 60 and 60' towards the rails RN and RN'. However if a frame be raised from its fully closed

position, rails RN and RN' being fastened to the frame shift slidably relative to tracks R and R' and the tapered portions of the bolts 60 are immediately unlocked, that is shifted or cammed inwardly by the upper wall of openings 61 and hence out of locking relation with tracks R and R' and of course against resistance of the cantilever springs 64, thereby permitting the latches 60 and 60' to yieldingly engage the intermediate tracks R and R' which are shifted upwardly by the actuating lugs 50 and 51 of the runners striking and abutting the lower ends LE and LE'. By such action tracks R and R' are raised and eventually fully telescope over guides G and G' at which time tracks R and R' and runners RN strike the overhanging stop lugs 57 and at which time the window is fully opened.

On closing of a window frame F, runners RN and RN' are slidably guided downwardly relative to the tracks R and R' and eventually latches 60 and 60' interlock with openings 61 of the tracks R and R', thereby driving the latter downwardly relative to the guides G and G' until lugs 35 and 35' of tracks R and R' meet the fixed stop 36 and 36' of the guides G and G' at which time the window frame is fully closed and resting on support S.

By the present invention, quick access may be had with convenience to all parts of the work surface WS to provide for larger working areas since the telescoping members RN and R and RN' and R' may be easily collapsed over the guides G and G', and conveniently may be easily extended for effectively closing the fume hood.

Various changes may be made in the details of construction and arrangement of parts without departing from the spirit of the invention or sacrificing any of the advantages thereof inherent therein.

I claim:

1. In a window arrangement for cooperating with a fume hood, a frame movable towards or away from a working surface of said hood, spaced guide means, spaced means fixedly sustaining said guide means appreciably spaced above said work surface, spaced channel shaped track means slidably retained by said guide means, and spaced channeled runners fastened to the sides of said frame and slidably straddling and guided by said track means.

2. In a window arrangement for cooperating with a fume hood, a frame movable towards or away from a working surface of said hood, spaced guide means, means fixedly sustaining said guide means appreciably spaced above said work surface, spaced track means telescopically receiving and slidably retained by said guide means, and spaced channeled runners fastened to the sides of said frame and telescopically receiving and slidably guided by said track means.

3. In a window arrangement for cooperating with a fume hood, a frame vertically movable towards or away from a substantially horizontal working surface of said hood, spaced and vertically arranged substantially C shaped guide means, means fixedly sustaining said guide means appreciably spaced above said work surface, spaced and substantially reverse C shaped and vertically disposed tracks telescopically receiving and slidably retained by said guide means and adapted to be projected below the latter, spaced channeled and vertically arranged runners fastened to the sides of said frame and telescopically receiving and slidably guided by said tracks; and

means to limit the projection of said tracks below said guide means.

4. In a window arrangement for cooperating with a fume hood, a frame vertically movable towards or away from a substantially horizontal working surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically arranged runners fastened to the sides of said frame and telescopically receiving and slidably guided by said tracks, means to limit the projection of said tracks below said guide means, and means carried by said runners for raising said tracks vertically towards said guide means and away from said work surface.

5. In a window arrangement for cooperating with a fume hood, a frame vertically movable towards or away from a substantially horizontal working surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically arranged runners fastened to the sides of said frame and telescopically receiving and slidably guided by said tracks, means to limit the projection of said tracks below said guide means, means carried by said runners for abutting the lower ends of said tracks for elevating the latter towards said guide means and away from said work surface, and said guide means having means to prevent upward displacement of said tracks and runners beyond the elevation of said guide means.

6. In a window arrangement for cooperating with a fume hood, a frame vertically movable towards or away from a substantially horizontal working surface of said hood, manipulatable means carried by said frame, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically arranged runners fastened to the sides of said frame and telescopically receiving and slidably guided by said tracks, means to limit the projection of said tracks below said guide means, means carried by said runners and responsive pursuant to an upward thrust on said manipulatable means for raising said runners towards said guide means and away from said work surface, and stop means overhanging said guide means to prevent upward displacement of said runners and tracks beyond the elevation of said guide means.

7. In a window arrangement for cooperating with a fume hood, a frame vertically movable towards or away from a substantially horizontal working surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically arranged run-

ners fastened to the sides of said frame and telescopically receiving and slidably guided by said tracks, means to limit the projection of said tracks below said guide means, and locking means 5 automatically effective on downward displacement of said runners relative to said guide means for bodily shifting said tracks with said runners and towards said working surface.

8. In a window arrangement for cooperating with a fume hood, a window frame vertically movable towards or away from a substantially horizontal working surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically ar- 10 ranged runners fastened to the sides of said frame and telescopically receiving and slidably guided by said tracks, means to limit the projection of said tracks below said guide means, lugs carried by the lower portions of said runners for 15 shifting said tracks away from said surface and towards said guide means on opening of said frame, and laterally extending lugs projecting from said guide means to prevent displacement of said tracks and runners beyond the upper end 20 of said guide means at the completion of the opening of said frame.

9. In a window arrangement for cooperating with a fume hood, a window frame vertically movable towards or away from a substantially horizontal working surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter, spaced channeled and vertically ar- 25 ranged runners fastened to the sides of said frame and telescopically receiving and slidably guided by said tracks, means to limit the projection of said tracks below said guide means, lugs carried by the lower portions of said runners for shifting said tracks away from said surface and towards said guide means on opening of said frame, 30 stop means at the upper part of said guide means to prevent displacement of said tracks and runners beyond said guide means at the completion of the opening of said frame, and locking means operable on downward displacement of said runners to shift said tracks bodily with said runners.

10. In a window arrangement for cooperating with a fume hood, a window frame vertically movable towards or away from a substantially horizontal surface of said hood, spaced and vertically arranged guide means, means fixedly sustaining said guide means appreciably spaced above said work surface, spaced channel shaped and vertically disposed tracks telescopically receiving and slidably retained by said guide means and adapted to be projected below the latter and having openings intermediate the ends thereof, spaced channeled and vertically arranged runners fastened to the sides of said frame and telescopically receiving and slidably guided by said tracks, spring controlled latching means carried at the upper parts of said runner for interlocking with the walls of said openings to shift said tracks below said guide means on shifting of said runners towards said surface, means to limit 40 the projection of said tracks below said guide 45 50 55 60 65 70 75

means, lugs carried by the lower portions of said runners for shifting said tracks away from said surface and towards said guide means on opening of said frame, stop means to limit displacement of said tracks and runners at the completion of the opening of said frame, and said latching means having means adapted to be cammed by walls of said openings to unlock said tracks on displacement of said runners away from said surface.

11. In a window arrangement for cooperating with a fume hood, window frames selectively and severally vertically movable towards or away from a substantially horizontal working surface of said hood, pairs of spaced and vertically arranged guide means, means fixedly sustaining said guide means appreciably spaced above said work surface, pairs of spaced channel shaped and vertically disposed tracks telescopically receiving and slidably retained by said pairs of said guide means and adapted to be projected below the latter, pairs of spaced channeled and vertically arranged runners fastened to the sides of said frames and telescopically receiving and slidably guided by said pairs of tracks, means to limit the projection of said tracks below said guide means, lugs carried by the lower portions of said runners for shifting said tracks away from said surface and towards said guide means on opening of said frames, stop means to limit displacement of said tracks and runners at the completion of the opening of said frame, and juxtapositioned runners of adjacent pairs of said runners having overlapping portions to facilitate guiding of said juxtapositioned runners relative to each other.

12. In a window arrangement for cooperating with a fume hood, window frames selectively and severally movable towards or away from a substantially horizontal working surface of said hood, a pair of spaced and vertically arranged guide means for each of said frames, means fixedly sustaining said guide means appreciably spaced above said work surface, a pair of spaced channel shaped and vertically disposed tracks from each of said frames and telescopically receiving and slidably retained by said guide means of respective frames and adapted to be projected below said guide means, a pair of spaced channeled and vertically arranged runners for each of said frames and fastened to the sides thereof and telescopically receiving and slidably guided by said tracks of respective frames, means to limit the projection of said tracks below said guide means, lugs carried by the lower portions of said runners of respective frames for shift-

ing said tracks of the latter away from said surface and towards said guide means of respective frames on opening of said frames, stop means integral with said guide means to prevent displacement of said tracks and runners beyond said guide means at the completion of the opening of said frames, and said runners and tracks of all of said frames adapted to be shifted away from said surface and towards said guide means to unobstruct the separation between all of said guide means and working surface.

13. In a window arrangement for cooperating with a fume hood, window frames selectively and severally movable towards or away from a substantially horizontal working surface of said hood, a pair of spaced and vertically arranged guide means for each of said frames, means fixedly sustaining said guide means appreciably spaced above said work surface, a pair of spaced channel shaped and vertically disposed tracks for each of said frames and telescopically receiving and slidably retained by said guide means of respective frames and adapted to be projected below said guide means, a pair of spaced channeled and vertically arranged runners for each of said frames and fastened to the sides thereof and telescopically receiving and slidably guided by said tracks of respective frames, means to limit the projection of said tracks below said guide means, lugs carried by the lower portions of said runners of respective frames for shifting said tracks of the latter away from said surface and towards said guide means of respective frames on opening of said frames, stop means to limit displacement of said tracks and runners at the completion of the opening of said frames, said runners and tracks of all of said frames adapted to be shifted away from said surface to unobstruct the separation between all of said guide means and working surface, and means for disengageably locking said runners and tracks of respective frames to bodily move said last mentioned runners and tracks towards said working surface.
